UNITED STATES PATENT OFFICE.

JAMES FATKIN, OF GULCH, COLORADO.

WRENCH.

SPECIFICATION forming part of Letters Patent No. 663,162, dated December 4, 1900.

Application filed April 25, 1900. Serial No. 14,243. (No model.)

To all whom it may concern:

Be it known that I, JAMES FATKIN, a citizen of the United States, residing at Gulch, in the county of Pitkin and State of Colorado, have 5 invented certain new and useful Improvements in Wrenches; and I do hereby declare the following to be a full, clear, and exact description of the invention, such as will enable others skilled in the art to which it appertains 10 to make and use the same.

This invention relates to certain new and useful improvements in wrenches for pipes, rods, tubes, nuts, and the like, and more particularly to a modified construction of a type 15 of wrenches shown in certain other applications filed by me of even date herewith, wherein the movable jaw has both a sliding and swinging movement relative to a fixed jaw, whereby when the said jaws are adjusted 20 to grasp a pipe, rod, tube, or nut a proper manipulation of the handle will cause the movable jaw to grasp the object to be turned and upon a reverse movement of the handle the grip will be instantly released.

25 In the accompanying drawings, Figure 1 is an edge view of a wrench embodying my invention. Fig. 2 is a side elevation thereof. Fig. 3 is a partial sectional elevation with a portion of the operating-handle omitted and 30 shows the movable jaw in section. Fig. 4 is a side elevation of a slightly-modified form of wrench with a part of the handle broken away. Fig. 5 is a section on line 55 of Fig. 4. Figs. 6 and 7 are side elevations of other 35 slightly-modified forms of the improved wrench, parts of the handle and fixed jaw being omitted. Fig. 8 is a cross-section through the handle, the cheek-pieces being shown in elevation and the movable jaw being omitted. 40 Fig. 9 is a cross-section through the movable jaw on line 99 of Fig. 2, with the screw omitted and showing the groove and end seat for the screw. Fig. 10 is an end view of the movable jaw with the screw omitted. Figs. 11, 45 12, and 13 are a side elevation, an end elevation, and bottom plan view, respectively, of the preferred form of nut. Fig. 14 is a bottom plan view of a modified form of nut; and 50 Fig. 15 shows in side and end elevation, respectively, still another slightly-modified form of nut as used in the construction of wrench shown by Fig. 7.

Similar letters of reference indicate similar parts throughout the several views.

In the drawings, A represents the handle 55 of the wrench, which may be of a size and shape adapted to the particular use for which it is intended. At its extreme end the handle carries a stationary or fixed jaw A' at a pre-determined angle to the handle and having a 60 notched face a. Rising from the handle, on each side thereof and at a suitable distance from the jaw A', are the two cheek-pieces a' a', between which the movable jaw B is adapted to have a sliding movement, as will herein- 65 after appear. The movable jaw B has a serrated face b, which in the operation of the wrench is adapted to coact with the face a of the fixed jaw A'. Projecting rearwardly from the face b is the body portion B', provided 70 with the slot b', extending longitudinally thereof, said body portion being adapted to fit between and be guided by the cheek-pieces a' a'. Carried by said body portion B' of the movable jaw, and preferably seated in a re- 75 cess or groove b¹³ formed therein below the lower face of the slot b', is a screw B², the forward end b² of which is seated in a socket b³ in the jaw in such manner that any thrust upon the jaw will be directly transmitted to 80 the screw lengthwise thereof. At its opposite end the movable jaw is provided with a bearing b⁴, in which the rear unthreaded portion b⁵ of the screw B² is mounted to turn freely, the end of the screw being extended beyond 85 the said bearing and having fixed thereto in any appropriate manner the knurled head b⁶.

In order to prevent endwise movement of the screw B² in the movable jaw, the unthreaded bearing portion b⁵ thereof is provided with a 90 circular groove b⁷, a complementary recess or groove b⁸ being also formed in the bearing b⁴ of the movable jaw, and into the opening thus formed is inserted a key b⁹ in such manner that said key while permitting free rotation of the screw in its bearings will prevent endwise movement thereof with relation to the movable jaw.

Seated in the slot b' of the movable jaw is a nut C, preferably provided on its under face 100 with a screw-threaded groove c, adapted to be engaged by the threads of the screw B². This nut fits between the cheek-pieces a' a', to which it is loosely connected by a pivot-

pin c' , which passes through a hole c^2 in the nut above the screw-threaded groove c . At each end the nut C is provided with projections c^3 , which extend beyond the sides of the body portion of the movable jaw and embrace and bear upon the edges of the cheek-pieces a a' .

From the construction and arrangement described it will be obvious that by manipulation of the screw B^2 by means of the knurled head b^6 the movable jaw B may be moved back and forth with relation to the fixed jaw A' , thereby adjusting said jaws to grasp a pipe, rod, tube, or the like, as at P , Fig. 3, and that movement of the handle A in the direction of the arrow s will cause the movable jaw to turn on the pin c' as a center, thus clamping the pipe, tube, or rod with a firm grip between the faces a and b of the jaws. A reverse movement of the handle in the direction of the arrow s' will turn the movable jaw on the pin c' , thus separating the jaws and promptly releasing the object gripped. As the handle is moved to grip the pipe, tube, or rod between the jaws strain will be put upon the movable jaw, tending to separate the two faces a and b , which strain, through the screw B^2 , will be transmitted to the nut C and from it to the cheek-pieces a a' through the forward pair of the projections c^3 c^3 , which thus closely relieves the pivot-pin c' .

In order to provide for the proper range of swinging movement of the movable jaw on the pin c' , and thereby secure greater efficiency in the gripping action of the jaws, the portion of the handle between the cheek-pieces is cutaway or beveled, as at d , although this may not always be necessary, and, in fact, depends upon the height of the pin connection between the cheek-pieces and nut C and the range of swinging movement desired for the movable jaw.

While I have described the above as the preferred embodiment of my invention, yet the construction is susceptible of modification and change. As, for instance, instead of placing the screw B^2 in a recess b^{13} in the body portion of the movable jaw such screw, as illustrated in Figs. 4 and 5, might be placed in a similar recess in the upper wall of the slot b' , in which case the nut C would be provided on its upper face with a threaded groove to engage the screw. In this case the pin c' will of course be passed through the nut below the threaded groove. Instead of the screw B^2 passing through a groove in the upper or lower faces of the nut it may, if desired, pass directly through a screw-threaded hole therein, as indicated in Figs. 7 and 15,

in which B^{12} is the screw, and C^5 is the nut, having the projections c^3 c^3 at each end, as before, but being provided with a central longitudinally-threaded hole c^{10} .

Since the strain to which the movable jaw is subjected is always lengthwise of the wrench, tending to force the jaws apart, it is not necessary to provide the nut with projections c^3 c^3 at each end thereof. In fact, as illustrated in Fig. 6, the lugs or projections c^3 c^3 at one end of the nut may be omitted altogether, in which case the lugs c^{13} on the opposite end of the nut would, as before, engage the forward edges of the cheek-pieces.

By pivoting the sliding jaw to the cheek-pieces loosely and providing the nut with projections to engage the cheek-pieces the pivot-pin c' is relieved of all strain.

It will be noticed that in the embodiment of the invention shown in Figs. 4 and 5 the clamping-faces of the movable and fixed jaws are substantially parallel when the said jaws are in the normal or open position. This feature is of particular advantage for hexagonal or other straight-faceted nuts.

Having thus described my invention, what I claim is—

1. A wrench, comprising a handle provided with cheek-pieces projecting therefrom and a fixed jaw formed at an angle to said handle beyond said cheek-pieces, a movable jaw provided with a longitudinal slot, and adapted to travel toward and from the fixed jaw in the space between the cheek-pieces and said fixed jaw, said movable jaw fitting between the said cheek-pieces, a nut in the slot of said jaw and pivotally connected with the cheek-pieces, said nut having lateral projections or lugs to engage the outer edges of the cheek-pieces, and a screw carried by said jaw and engaging said nut, substantially as set forth.

2. A wrench comprising an operating-handle provided with cheek-pieces projecting therefrom and a fixed jaw formed at an angle to said handle beyond the cheek-pieces, a movable jaw provided with a longitudinal slot, said movable jaw fitting between said cheek-pieces, and having its clamping-face substantially parallel to the clamping-face of the fixed jaw, a nut in the slot of the movable jaw, and having laterally-projecting portions at opposite ends embracing said cheek-pieces, and a screw carried by the movable jaw and engaging said nut; substantially as set forth.

In testimony whereof I affix my signature in presence of two witnesses.

JAMES FATKIN,
